(57) **CLAIM**

The ornamental design for a connector housing, as shown and described.

DESCRIPTION

We further expressly incorporate by reference the specification and drawings of related application U.S. patent application Ser. No. 13/171,288, filed Jun. 28, 2011, entitled "End Fitting for a Cable With Sealing Protrusion and Enclosure Assembly With End Fitting," the disclosure of which is expressly incorporated by reference herein.

FIG. 1 is a top and left side perspective view of a connector housing showing our new design in environmental use;

FIG. 2 is another top and left side perspective view thereof;

FIG. 3 is a bottom and left side perspective view thereof;

FIG. 4 is a bottom and right side perspective view thereof;

FIG. 5 is a top plan view thereof; and,

FIG. 6 is a side elevation view thereof.

The broken lines shown represent unclaimed subject matter and form no part of the claimed design.
